United States Patent

Des. 238,274

Patented Dec. 30, 1975

238,274

VALVE BASE

Roger D. Slagel, 1301 SW. 20th Terrace,
Fort Lauderdale, Fla. 33312

Filed July 16, 1973, Ser. No. 379,464

Term of patent 14 years

Int. Cl. D23—01

U.S. Cl. D23—19

Fig. 1

Fig. 2

Fig. 3

Fig. 4

FIG. 1 is a top plan view of a valve base showing my new design;

FIG. 2 is a cross sectional view thereof taken along the line 2—2 of FIG. 1;

FIG. 3 is a side elevational view thereof; and

FIG. 4 is a bottom plan view thereof.

I claim:

The ornamental design for a valve base, substantially as shown.
